KNITTING DARNING MACHINE

Paul Obermayr, Mittweida, Germany

Application May 20, 1937, Serial No. 143,659
In Germany May 22, 1936

11 Claims.

(Cl. 66—2)

The invention relates to a machine for mending knitted articles or fabrics by which machine knitting loops or meshes can be formed, and which works in the manner of a one-thread sewing machine.

The invention has for its main object to so construct the knitting darning machine that the formed series of meshes or loops can be locked or bound off at any moment.

For this purpose in accordance with the invention two loopers for the formation of meshes are provided, adapted to work alternately viz. a knitting looper for the formation of meshes and a linking looper for locking the last series of meshes.

A further object of the invention is to so construct the mesh forming and mesh retaining parts that they are adapted to cooperate selectively with both loopers.

Further objects and advantages of the invention will now be described, the drawings showing a constructional example.

Fig. 1 shows the machine in side elevation and partly in section;

Fig. 1a shows diagrammatically in exaggerated manner the relative position of the needle axis to the needle bar axis during the knitting work proper;

Fig. 1b shows said relative position during the work of locking or binding off;

Figs. 2 and 3 show the feed mechanism for the work table;

Fig. 4 shows the ratchet mechanism for the feed;

Fig. 5 shows the sinker bed with sinkers, knitting looper and needle in the operative position;

Fig. 6 shows the mounting of the linking and knitting loopers;

Fig. 7 shows a part of the table in plan on an enlarged scale;

Figs. 8-11 show different positions of the mesh forming parts;

Fig. 12 shows an elevation of the eccentric disc for driving the sinkers;

Fig. 13 shows an elevation of the eccentric disc for driving the looper;

Fig. 14 shows an elevation of the switch-over device for the linking looper.

In one method of carrying out the invention, the frame of the machine is similar to that of a single-thread sewing machine. This frame is provided with a housing 1 in which terminates the main shaft 2. Mounted on the main shaft is a double cam disc 3 (Figs. 1, 2 and 13) which by means of lever or similar element 4 actuates

the hook sinkers 5 and also imparts an oscillatory movement to the knitting looper 6. For controlling the lever 4 the disc 3 has an orbital cam groove 3a (Fig. 12) into which a pin 4a of the lever engages. The knitting looper 6 has a hook 6a (Fig. 13), and is connected with a roller 6b, connected in turn with a pin 75 which engages into a second orbital groove 3b of the disc 3 whereby the looper is given a rocking movement. A gear wheel 7, mounted on the main shaft 2 to rotate therewith, meshes with a gear wheel 8 (Fig. 6) of the linking looper 9, and drives the latter. The knitting and linking loopers are mounted on a common plate or disc 16 which is rotatably mounted in the housing wall 1 by means of a bush 11. The work drum encloses the housing 1, on which it is rotatably mounted. The work-drum 12 carries the sinker bed 13, in which the sinkers 5 are guided somewhat obliquely (Fig. 5), and an internal ring gear 14. The cover plate 15 of the sinker bed 13 is provided with pins or like tooth-like elements 16 (Fig. 7) at the needle slot, said pins being located between the individual sinkers 5. A disc 17 bearing on the lever 4 and secured to the housing 1, holds the hook sinkers not engaged by the lever 4 in the closed or raised position.

A bevel gear wheel 18 fixed to the main shaft is coupled to the bevel wheels 19 and 20 mounted respectively on pins 21 and 22. Connected in an axially slidable manner with the bevel wheels 19, 20 are two Maltese cross pin wheels 23 and 24. The worm 25 meshing with the ring gear 14 is provided on either side with a star wheel 26 and 27 engaged alternately by the pin wheels 23 and 24. This is accomplished by means of the ratchet mechanism shown in Fig. 4. The wall 28 of the work drum 12 carries an adjustable pin 29, functioning alternately to release the two pawls 30 and 31. The pawls are pivoted on pins 32 and 33, and are under spring pressure by spring wires 34 and 35. The noses 30a and 31a of the pawls 30, 31 engage the recesses of the slidable plate 36. The pins 36a and 36b on the plate 36 serve as abutments for the spring 37. Two forks 38 and 39 secured to the plate 36 engage the two pin wheels 23 and 24.

On the bush 11 of the looper plate 10 externally of the housing is a wide adjusting ring 40 surrounded by a fixed ring 41 of the housing wall. The adjusting ring 40 carries a spring-pressed locking slide 42, the nose 43 of which engages the slot of the adjusting ring 40 and one of the two slots 54 and 55 (Fig. 14) of the ring 41. A disc 44 is mounted on the main shaft 2 55

in a depression in the adjusting ring 40 and is provided with a recess 45. Fixed to the adjusting ring 40 is the hood 46 in which is anchored the locking plate slide spring 47. The needle 48 as shown in Fig. 1 is inserted somewhat obliquely in the needle bar 49. Fig. 1a shows in exaggerated manner the angle between the axis 50a of the needle bar and the axis of the needle in the knitting position 48a. The needle is connected to a pin 50 passing through the needle bar. This pin is provided with a cap 51 accommodating a spring-pressed plate 52 with ball 53 for locking the pin.

The operation of the machine is as follows:—

With the needle in the raised position, the recess 45 of the disc 44, which rotates with the main shaft 2, is caused to register with the locking slide 42. The latter is pressed inwardly and can then be rotated as far as the knitting looper slot 55 (Fig. 14) on the ring 41 by means of the hood 46 connected to the looper plate 10, whereupon the slide springs into said slot. The knitting looper 6 having thus been brought into the operative position, is secured against rotation by the slide 42, and the disc 44 is again released. The defective article, for example a stocking, is pushed over the work-drum so that the hole to be darned is situated behind the needle slot, in order that the first course will commence in the sound knitting. The needle 48 is turned so that the thread running through the eye lies on the knitting looper side. The needle now plunging downwards upon the rotation of the hand wheel passes with the rearwardly situated hook sinker into the lower position, the sinker yielding somewhat obliquely (Fig. 5) in order not to impede the thread in its loop-forming operation (Figs. 8 and 9). The knitting looper is now oscillated to slide over the sinker and past the needle, and on its return path takes the thread with it, in consequence of the barb, for laying the thread in the hook sinker (Figs. 5, 8, 9). During the subsequent upward movement of the needle, the sinker also moves up with the thread, the sinker hook comes behind the holding bar 54, whereby the loop is secured from slipping out (Figs. 10 and 11). Before the needle reaches the highest position the knitting looper again makes the same oscillatory movement in order to release the thread which is still hanging in the hook of the looper (Figs. 10 and 11), said thread being now drawn tight by the further pull of the needle. In the highest position of the needle which has now been reached, the pin 23a (Fig. 3) of the pin wheel 23 engages a slot of the star wheel 26, thus producing a quarter of a revolution of the worm 25 which advances the ring gear 14 and hence the work-drum by one sinker interval. The working cycle now takes place from sinker to sinker in the manner described above until the first course of loops has been laid. Due to the continued movement of the work-drum 12, the adjustable pin 29 comes against one arm of the spring 37, tensions the latter around the pin 36b of plate 36 and on the further movement releases the pawl 31, whereby the plate 36 and also the pin wheels 23 and 24 coupled to it by the forks 38 and 39 are changed over. Since in consequence of the bevel gear drive, the two pin wheels rotate in opposite directions, reversal of the direction of the feed of the work-drum now takes place, since the pin wheel 24 is now coupled to the star wheel 27, while the pin wheel 23 runs idle. The needle 48 now passes seriatim through the loops

hanging in the hook sinkers, and due to the lowering of the hook sinker, the loop already suspended in the needle is removed from the hook and the new loop is laid after the working cycle already described until the hole or the defective part of the article has been mended. Due to the oblique position of the needle 48, each loop after leaving the hook sinker is forced away from the holding bar 54, while the pins 16 located between the hook sinkers prevent the fabric from being pulled or dragged into the needle slot, so that the work can be carried out without a clamping frame or the like means. After completion of the repair, and with the needle in the raised position, the locking slide 42 is released, and by means of a partial revolution of the hood 46 connected to the looper plate 10, the linking looper 9 is brought into the working position. This can be done only when the needle is outside the drum because only then the recess 45 of the disc 44 is in the position permitting the necessary movement of the slide 42. By means of the cap 51 on the needle bar 49, the needle 48 is rotated through half a turn, so that the axis of the needle now has the position 48b (Fig. 1b) and the thread running off is now brought to the opposite side within reach of the linking looper which now makes the known linking or binding-off seam, but since at the same time the needle takes over the end loops hanging in the hook sinkers, the linking looper also binds off the latter loops. The work is thus completed. The width of the work may be varied as desired by adjustment of the pin 29, since when the pin is in a high position it reaches a pawl sooner than when it is in a lower position, and therefore the reversing of the feed is effected earlier or later as desired.

I claim:

1. A knitting darning machine constructed like a one-thread sewing machine, characterized by having, in addition to a knitting looper for the formation of knitting meshes, a linking looper adapted to be made operative instead of the knitting looper.
2. A machine as in claim 1, characterized by the fact that movably mounted sinkers used for retaining the meshes in the direction of the needle are guided obliquely to said direction by comblike sinker beds.
3. A machine as in claim 1, characterized by the fact that the needle is secured to the needle bar at an angle to the axis of the latter.
4. A machine as in claim 1, characterized by the fact that the needle bar with the needle secured thereto at an angle to the axis of said bar is adapted to be adjusted by rotation about said axis.
5. A machine as in claim 1, characterized by the fact that its work table is constructed in the form of a rotatable drum.
6. A machine as in claim 1, characterized by the fact that the rotation of its work table, constructed in the form of a drum, is made use of for bringing the sinkers one after the other into cooperation with the member provided for the actuation of said sinkers.
7. A machine as in claim 1, characterized by the fact that the knitting looper is constructed in the form of a rotatably mounted hook.
8. A machine as in claim 1, characterized by the fact that the knitting looper and the linking looper are mounted on a common rotatable disc.
9. A machine as in claim 1, characterized by

the fact that its work table, constructed in the form of a rotatable drum, is adapted to be rotated by means of a toothed ring secured thereto into which engages a worm adapted to be driven stepwise, corresponding to the distance of the sinkers, by means of a Maltese cross gearing.

10. A machine as in claim 1, characterized by the fact that its work table, constructed in the form of a rotatable drum, is adapted to be rotated by means of a toothed ring secured thereto into which engages a worm adapted to be driven stepwise, corresponding to the distance of the sinkers, in either of two opposite directions by means of either of two Maltese cross gearings

mounted for opposite rotation and engageable selectively with the worm.

11. A machine as in claim 1, characterized by the fact that its work table, constructed in the form of a rotatable drum, is adapted to be rotated by means of a toothed ring secured thereto into which engages a worm adapted to be driven stepwise, corresponding to the distance of the sinkers, in either of two opposite directions by means of either of two Maltese cross gearings 10 mounted for opposite rotation and engageable selectively with the worm, under automatic control through a stop connected with the drum.

PAUL OBERMAYR.
